UNITED STATES PATENT OFFICE.

SAMUEL A. ARMSTRONG, OF TORONTO, ONTARIO, CANADA, AND ARTHUR H. BLACKBURN, OF DOWNTON GROVE, ILLINOIS, ASSIGNEES TO UNDER-FEED STOKER COMPANY OF AMERICA, OF CHICAGO, ILLINOIS, A CORPORATION OF NEW JERSEY.

UNDERFEED FURNACE.

1,333,696.

Specification of Letters Patent. Patented Mar. 16, 1920.

Application filed June 9, 1919. Serial No. 302,822.

To all whom it may concern:

Be it known that we, SAMUEL A. ARMSTRONG and ARTHUR H. BLACKBURN, subjects of the King of Great Britain, residing at Toronto, Ontario Province, Canada, and Downers Grove, in the county of DuPage and State of Illinois, U. S. A., respectively, have invented certain new and useful Improvements in Underfeed Furnaces, of which the following is a specification.

Our invention relates to underfeed furnaces and, in some respects, particularly to side-dump, single-retort constructions, in which the fuel is fed rearwardly through the furnace from a single supply-hopper, is distributed laterally across the fire box floor and is laterally delivered, as ash, to dumps paralleling the furnace-sides.

Some of the objects of our invention are to increase materially the hitherto-attainable capacity of such furnaces making them available for boilers which hitherto would have required other and more expensive types of stoker-construction; to insure most effective and complete combustion of the fuel; to secure desirably uniform, regulated distribution of the fuel; and to attain many advantages of simplicity, ruggedness and economy of construction and ease of requisite erection, repair and replacement of parts.

To these ends, and others which will become apparent from the following description, our invention consists in the constructions and combinations, of novelty and advantage, hereinafter pointed out; reference also being had to the accompanying drawings showing a single embodiment of our invention for purposes of disclosure thereof.

40 In the drawings,

Figure 1 is a plan view of the firebox floor with parts broken away;

Fig. 2 is a longitudinal section;

Fig. 3 is a transverse section;

45 Fig. 4 is a fragmentary front elevation;

Fig. 5 is a twyer-lock detail.

The fuel is fed from an outside hopper 10, by a ram 11 through a throat 12 into a retort 13 which forms part of the fire box 50 floor that extends from the front-wall 14 to the transverse bridge wall 15. The ram, as shown, comprises a cylinder 16 opening endwise to the somewhat-flaring throat 12,

and having a top orifice to the hopper in the zone of reciprocation of a piston or plunger 55 17 which is reciprocated at proper intervals by a suitable power-device such as steam-engine 18. The plunger has an arm 19 depending through a cylinder-slot 20 and carrying cross-pin 21 to coact with a pusher, 60 or feed element, to be described. Thus far, only matters of common practice have been stated.

The fire-box floor divides the combustion chamber 22 above, from the central wind 65 box 23 and longitudinal, side ash-pits 24, below, the wind box 23, to which air under pressure is supplied by usual means (not shown) being separated from the flanking ash pits by longitudinal partitions 25. These 70 are preferably vertical frame members resting on the foundation and cross-connected by beams 26 on which the retort centrally bears through a foot-rib 27. On this framework most of the parts of the fire-box floor 75 work are supported.

The retort 13 has a main channel or fuel-trunk 30, preferably of flaring-sided, round-bottomed trough shape in cross-section with its bottom up-sloping somewhat from front 80 to rear and its rear end upsloped steeply and provided with a reentrant prow, or upwardly-inclined, sideways-flaring deflector 31, the upper edge of the main-retort casting preferably being substantially horizontal from 85 front to rear. From this main retort-trunk run lateral, or branch retorts 32—a suitable number of them (say four) on each side, preferably disposed in transversely-alining pairs on opposite sides of the trunk, and all 90 preferably at substantially right angles to the main channel. These branch retorts, as shown in Fig. 3, preferably have up-sloping bottoms, each bottom having an off set portion 33 or out-facing shoulder, and the 95 branches have down-sloping top-edges; the top and bottom slopes converging to union near the longitudinal plane of the partition 25. In cross-section (Fig. 2) the branch-retorts preferably flare upwardly from round- 100 ed bottoms, and their bottoms may merge into the bottom curves of the main-trunk as shown in Fig. 3. The branch retorts are preferably quite close together—making the side-wall posts 34 of the main retort narrower than the branch-retort mouths, and 105

each branch retort is long, as compared with its width, preferably at least several times as long as its width or depth. The rearmost branch retorts have their rear sides merging 5 into the end wall of the main retort, so that fuel deflected by the prow 31 may enter them.

Marginally around all of the branch-retorts and the main-retort side-posts twyters 10 are provided, to deliver air from the wind-box below into the fuel, so that as green fuel is fed rearwardly along the trunk or main channel, and laterally through the several branch channels, it receives its air supply substantially throughout its entire progress in the fashion which is best characteristic of underfeed practice, namely above the lowest green fuel stratum and below the actively burning or partly consumed fuel. 15 This is of great advantage in many particulars, since the fuel along the zones adjacent the side dumps is not burned out until it is at the extreme margin of the combustion space, but comes across properly coked, receiving its air in ample quantity and in most effective manner, with the progressively-thinning under-stratum of fuel in the outer ends of the lateral branches fully fired and consumed before it reaches the ash dump 20 doors, and with a resultant intense-broad-spread fire throughout the whole effective floor-space, which enables a furnace thus constructed to serve a boiler of much greater capacity than does any part-underfed and 25 part-overfed (or grate) construction of the same floor-dimensions of which we are aware.

It is important, in a construction as above described, that the fuel-feed through the 30 relatively long main-trunk and long lateral-branches should be properly regulated and should be positive, to insure against clogging and to give the requisite quantitative supply and necessary fuel-movement through-out and also it is desirable that this feed should exert a strong clinker-breaking effect in the main and branch retorts. To these ends feeding devices supplemental to the ram are provided. The main retort 35 has therein a pusher rod 40, guided at 41, extending out below the throat and connected for variable-lost-motion to the plunger-arm 19 by two pivoted link-members 42, straddling the arm 19, resting on the 50 pin 21, united by a rear bolt 43, and carrying an adjustable stop-pin 44 to receive which a series of holes are made in the links. On this rod 40 the pusher heads 46 and 47 55 are adjustably secured by set screws 48, these heads being retort-bottom-fitting blocks with abrupt, nearly-vertical rear faces and steeply-inclined front-top surfaces, whereby they tend to push the fuel rearwardly on the in-stroke of the ram, and to lift the fuel 60 with clinker-breaking effect and side-feed- 65

ing tendency on the outstroke of said ram. By adjusting the pusher-heads along the rod the effective distribution of fuel may be modified and regulated to insure proper supply to all of the branch-retorts. Additional feeding devices are provided in the branch retorts, a pusher bar 50 slidably extending through the shoulder 33 of each branch-retort bottom, each such pusher having a head 51 and below the inboard portion of the retort bottom, having a rack 52. Each such rack coacts with a gear-sector 53 arranged on a shaft 54 for oscillation to reciprocate the pusher. 70 75

As an effective, preferred means for rocking the shafts so as variably to regulate the feeding-action of these auxiliary pushers, the rock-shafts 54, extended beyond the front wall, have levers 55 straddling a bar 56 reciprocable in harmony with the ram action as by a steam engine 57, said bar carrying adjustable stop blocks 58 for giving any desired lost motion in the operation of the rock shafts, so as to give different lengths of stroke to the pushers 50. These branch pushers are very effective in relieving the furnace of clogging or undue fuel-packing and they carry the fuel positively along the branch-lines beyond the distance that the coal could be made to progress by 80 the feeding action of the ram and main pushers. 85 90 95

In the construction of a retort system as described the trunk-retort 30 may be a casting with branch-retort stubs 60 integral therewith, flanged as at 61 to receive the flanged root-ends 62 of the branch retorts, each of which is a casting having at its leaving-end or outer extremity a flange 63 supported from the frame-member 25 through an interposed Z-beam 64, these parts being apertured as at 65 to receive twyer-tongues hereafter to be described. When these several parts are bolted together the firebox-floor, of especially solid and durable construction, is complete except for the twyer blocks. 100 105 110

Since the twyer blocks should be readily replaceable and yet must stand the strains of the combined longitudinal and lateral distribution of the coal-mass, their mounting for strength and ease of placement is important. Each sidepost 34 of the main retort has an apertured top-flange 66 and a lug or flange portion 67 preferably integral with the stub-flange that receives the bolted-on branch retort. This lug is apertured to give bearing to a trunnion 68 of a twyer lock having a lock bar 69 extending along the space between adjacent branch-retorts and having at its other end a trunnion 70 mounted in a bearing-block 71 on the Z-beam 64. A lever 72 at the other end of the lock enables its bar to be swung from the locking position shown in 115 120 125 130

Fig. 5 to an unlocking position. The several levers 72 along each side are connected by an operating rod 73 which extends through the furnace-front for exterior manipulation. The twyer blocks 75 capping the side posts of the main retort have closed bottoms with lugs 76 entering the apertured post-tops 66, and, outwardly extending hooks 77 for engagement with the appropriate lock-bar 69. These post-twyer-blocks have air openings toward the main and branch retorts and their outer sides are open to the contiguous twyer blocks along the branch retort sides. These side-twyer-blocks, 78, are arches (see Fig. 5) seated on the separated flanges of adjoining branch-retorts, each having an apertured cross-wall 79 having a locking hook 77. The end twyer blocks 80 may be T-shaped in plan, as shown, with locking hooks on their short stems, and with lugs 81 on their undersides to pass through the openings 65 in the retort-flanges, these lugs 81 being apertured to receive a key-rod 82 locking all the alining lugs in place and extending through the furnace front for easy removal from the outside.

Thus all of the twyer blocks mentioned are removably positioned but very strongly held; their release requiring only the withdrawal of rods 81 and the pulling outwardly of lock-operating rods 73 to swing all lock-bars 69 to unlocking position. The twyer blocks 83 along the front wall and bridge-wall are held in the fashion described, but to prevent clinker-adhesion along the fire-box walls they are preferably made high, steeply sloped, and with baffled air passages to compel the air to sweep under their exposed surfaces, as best shown at 83' in Fig. 2.

Ash removal may be variously accomplished, but the simple dump-doors 85, substantially covering the ash pits and reaching practically to side walls 86, and mounted on frame-carried rock shafts 87, exteriorly operatable by levers 88 to dump the ash, provide one simple and effective means for this purpose, any suitable ash-removal construction paralleling and close to the side walls being sufficient.

It will be understood that while we have described in detail a specific embodiment of our invention for full disclosure, and some details of which we may claim for their particular advantages, we do not desire to be understood as so limiting our invention in its broader aspects, as many changes in construction and arrangement may be made within the spirit of our invention and the scope of the appended claims.

We claim:

1. In an underfeed furnace, the combination of fire-box walls, ash removal means paralleling the side-walls, and a fire-box floor composed of a central retort and lat-

eral-branch retorts, the latter opening to the main retort at their inner ends and extending substantially to the ash-removal means at their outer ends, said main and branch retorts having marginal twyers along their sides and across their ends, adjacent the floor-level.

2. In an underfeed furnace, the combination of fire-box walls, ash removal means paralleling the side-walls, and a fire-box floor composed of a central retort and lateral-branch retorts, the latter opening to the main retort at their inner ends and extending substantially to the ash-removal means at their outer ends, said main and branch retorts having marginal twyers along their sides and across their ends, adjacent the floor-level, and said branch retorts tapering from approximately the main-retort depth at their inner ends to the twyer-level at their outer ends.

3. In an underfeed furnace, the combination of fire-box walls, ash removal means along the side-walls, and a fire-box floor composed of a main retort and lateral branch retorts opening thereto and extending substantially to the ash removal means, the tops of said retorts provided with inwardly directed twyers adapted to receive air from below the floor, and arranged on substantially a longitudinal level but laterally downsloping from the main retort, the bottom of said main retort being rigid and upsloping from front to rear and the bottoms of the branch retorts unsloping from the main retort bottom at their inner ends to the twyer-levels at their outer ends.

4. In an underfeed furnace the combination of a fire-box floor comprising a main longitudinal retort and lateral branch retorts, the latter opening into the former, fuel feeding means associated with said main retort and auxiliary fuel feeding means associated with the several branch retorts.

5. In an underfeed furnace the combination of a fire-box floor comprising a main longitudinal retort and lateral branch retorts, the latter opening into the former, longitudinally reciprocable fuel feeding means arranged to feed fuel longitudinally of the main retort, and laterally reciprocable auxiliary feeding means in the several branch retorts.

6. In an underfeed furnace, a fire-box floor comprising a main longitudinal retort and lateral branch retorts, the latter opening at their inner ends to the former; a feed ram for the main retort; and laterally reciprocable pushers in the branch retorts.

7. In an underfeed furnace, a fire-box floor comprising a main longitudinal retort and lateral branch retorts, the latter opening at their inner ends to the former; a feed ram for the main retort, pusher means

- in the main retort, and laterally reciprocable pushers in the branch retorts.
8. In an underfeed furnace, a fire-box floor comprising a main, longitudinal retort and lateral branch-retorts, each said retort portion having a rounded, closed, up-sloping bottom, and said branch retort bottoms provided with an offset portion; a feed ram for the main retort, feed-pushers for the branch retorts, each extending through the shoulder of the offset portion, and pusher operating means associated with the portions of said pushers outside of the branch-retorts.
9. In an underfeed furnace, a main retort, branch retorts leading therefrom, means for feeding fuel longitudinally of the main retort, pushers in the branch retorts and means for operating said pushers for variable throw.
10. A fire-box floor comprising a main retort and branch retorts opening thereto, detachable twyer blocks along the margins of the main and branch retorts, and common retaining means for the twyer blocks that are along a side-margin of a retort-branch.
11. In an underfeed furnace, a fire-box floor comprising a main retort casting having side-posts, branch retort castings opening to the main retort between said side-posts and having side-margins and sets of detachable twyer blocks spanning the space between and resting on the margins of, adjacent branch-retorts.
12. In an underfeed furnace, a fire-box floor comprising a main retort casting having side-posts, branch retort castings opening to the main retort between said side-posts and sets of twyer blocks spanning the space between and resting on the margins of, adjacent branch-retorts, said twyer blocks having depending locking lugs and movable means coöperating therewith to lock all twyer blocks of one such set.
13. In an underfeed furnace, twyer blocks having locking hooks, and a swinging lock bar for engaging and disengaging said hooks, respectively to lock and release the twyer blocks.
14. In an underfeed furnace, the furnace walls, a fire-box floor having a main retort and lateral branch retorts opening therefrom, twyer blocks along the edges of said retorts, locking means for simultaneously engaging or disengaging a plurality of said twyer-blocks and operating means for the locking means operable exteriorly to the furnace walls.
15. In an underfeed furnace, the combination of the fire-box walls, a main retort, lateral branch retorts paralleling the front and rear walls, and twyer blocks along the margins of said retorts, the twyer blocks adjacent the front and rear walls upsloping steeply to said walls, and contacting therewith to present cool non-clinking surfaces at the ends of the fuel-beds.
16. In an underfeed furnace, a main retort and lateral branch retorts opening thereto, said main retort having its rear end formed into a reëntrant prow having steeply up-sloped and laterally flaring fuel-deflecting side-surfaces that, at their outer margins merge into the rear side-walls of the rearmost branch retorts; and fuel feeding means for propelling fuel longitudinally along the main retort for deflection of part thereof by said prow into the rearmost branch retorts.
17. In an underfeed furnace, a main-retort casting having separated side posts and a plurality of separate lateral-branch-retort castings, each opening between and secured to two of the main-retort side-posts.
18. In an underfeed furnace, a main-retort casting having separated side posts and a supporting frame carrying said main retort and the outer ends of said branch retorts, said frame including side-walls carrying the branch-retort ends and cross connections carrying the main retort.
19. In an underfeed furnace, a main retort having side posts, lateral branch retorts opening between said posts and having their side walls spaced apart; twyer blocks mounted along said spaced side-walls, other twyer blocks mounted across the ends of said branch retorts, and respective retaining means for the groups of side-twyer-blocks and end-twyer-blocks all extending to and releasable from the front of the furnace.

SAMUEL A. ARMSTRONG.
ARTHUR H. BLACKBURN.
